**METHOD OF MAKING STRESS-RELIEVED
METAL TANKS**

No Drawing. Filed July 15, 1966, Ser. No. 565,399
11 Claims. (Cl. 29—404)

ABSTRACT OF THE DISCLOSURE

A method of forming and stress-relieving in place a metal tank on a transport carrier, e.g., a barge, for the transportation of liquefied gases such as ammonia, by joining together metal plates in the place of operation, filling the formed tank with a liquid such as water for approximately an hour and having the filling liquid exert a stress-relieving pressure of not less than the designated tank pressure and not more than twice the designated tank pressure, the stress-relieving pressure being caused by the inherent weight of the filling liquid solely or in combination with applied external pressure. Stress-relief is thereby gotten without resort to the relatively complex and expensive prior art methods of stress-relief, e.g., annealing the tank in an oven at high temperatures.

This patent application is a continuation-in-part of the parent application for "Waterborne Freight-Carrying Vehicles" Ser. No. 396,817, filed Sept. 14, 1964, now Patent No. 3,280,779, granted Oct. 25, 1966.

The invention relates generally to an improved method of making metal tanks, and more specifically, to making stress-relieved metal tanks for the storage of liquefied gases.

In forming and shaping metal plates into the required shapes and in joining the plates to make a tank, especially a tank that is fabricated in the place of operation and in close conformance with the shape of a carrier such as the barge described in the parent application, internal stresses are set up in the metal that often results in the failure of the fabricated tank under operating conditions unless these stresses are relieved. Heretofore internal stresses have been relieved by annealing the completed tank in an oven of sufficient size at a temperature of about 1250 degrees F. Annealing thus precludes fabrication in the place of operation.

It is an object of the invention to provide a positive method of making stress-relieved metal tanks in the place of operation that are free from stress failure caused by internal-stresses.

Other objects and a fuller understanding of the invention may be had by referring to the following description and claims.

Metal plates of suitable tensile strength for the temperatures and pressures to be operationally encountered by the completed tank are formed and shaped into constituent parts of a tank. In the forming and shaping internal stresses are set up in the metal plates. The plates are joined together to make a liquid-tight tank, and the joining adds further to the internal stresses already set up in the metal, regardless of whether the joining is accomplished by welding or riveting. The completed-in-place tank is then filled with a liquid, preferably water as most economical, at or above ambient temperatures. The liquid filling the tank exerts a pressure therein that is a function of the specific gravity of the liquid and the mass of liquid required to fill the tank. If the capacity of the tank is such that the mass of the filling liquid exerts a pressure greater than the operational pressure but not more than twice said operational pressure, the tank will be relieved of its internal stresses. If the filling liquid

2

exerts a pressure less than the operational pressure, external pressure may be applied to the filling liquid in the tank by any of various well known means to raise the filling liquid pressure within said range of stress relieving pressures, or a filling liquid with a sufficiently higher specific gravity may be used to fill the tank to obtain the same results. If the filling liquid exerts a pressure more than twice the operational pressure, a liquid with a lower specific gravity to bring the tank pressure within the stated range of stress relieving pressures should be used. For best results the tank should be allowed to remain full for a period of about one hour.

Although we have described the invention with a certain degree of particularity, it is understood that the present disclosure has been made only by way of example and that numerous changes in details of steps and the arrangement thereof may be resorted to without departing from the spirit and the scope of the invention as hereinafter claimed.

20 What is claimed is:

1. The method of making a stress-relieved metal tank comprising: forming and shaping metal plates as constituent parts for fabricating said tank; joining said plates to make a liquid-proof tank; filling said tank with a liquid mass having a specific gravity for said mass of filling liquid to exert a pressure of not less than the designed tank pressure and not more than twice said pressure; and maintaining said filling liquid in said tank for a period of time to relieve stresses in said tank.

25 2. The method of making a stress-relieved tank as described in claim 1 wherein the step of filling said tank with a liquid comprises: using water to fill said tank; and applying an amount of pressure on said filling water to bring the pressure in said tank within said stress-relieving range of pressures.

3. The method of making a stress-relieved metal tank as described in claim 1 wherein said constituent parts for fabricating said metal tank are joined to form said tank in its place of operation.

40 4. The method of claim 1 in which said period of time is at least one hour.

5. In the fabrication of a metal tank having a designed tank pressure, a method of forming and stress-relieving said tank comprising the steps of:

45 (a) providing pre-formed metal elements to be used as constituent parts of said tank;
(b) by joining said elements together to form said tank, substantial internal stresses being set up in said tank during the forming of said tank; and
(c) stress-relieving said tank by filling said tank with a liquid mass and having said liquid mass exert a pressure on said tank of not less than the designed tank pressure and not more than twice said designed tank pressure, whereby said tank is stress-relieved.

55 6. The method of claim 5 in which the stress-relieving pressure is had by using a sufficient amount of filling liquid mass having a specific gravity which will, without external pressure being applied, exert a pressure on said tank of not less than the designed tank pressure and not more than twice said designated tank pressure.

7. The method of claim 5 in which the proper stress-relieving pressure is obtained by using a filling liquid mass in conjunction with the application of external pressure.

60 8. The method of claim 5 in which the filling liquid mass is water.

9. The method of claim 5 in which the filling liquid mass is allowed to remain in said tank for a period of about one hour.

70 10. The method of claim 5 in which the forming and stress-relieving of said tank are done in its place of operation.

11. In the manufacture of a transport carrier suitable for carrying liquefied gases and having at least one metal tank, the method of:

- (a) forming a metal tank in its place of operation on said transport carrier by joining together metal plates, internal stresses being set up in said tank during said forming; and
- (b) positively stress-relieving said tank in its place of operation by filling said tank with water and having the water exert a pressure of not less than the designed tank pressure and allowing said water to remain in said tank for at least one hour, whereby said tank is stress-relieved without resort to the relatively complex and expensive prior art methods of stress-

relieving, e.g., annealing in ovens at high temperatures.
